UNITED STATES PATENT OFFICE.

JAMES E. WHITE, OF MALDEN, MASSACHUSETTS.

DOOR-SECURER.

SPECIFICATION forming part of Letters Patent No. 350,332, dated October 5, 1886.

Application filed March 31, 1886. Serial No. 197,347. (No model.)

To all whom it may concern:

Be it known that I, JAMES E. WHITE, of Malden, in the county of Middlesex and State of Massachusetts, have invented certain Im-
5 provements in Door-Fasteners, of which the following is a full, clear, and exact description, reference being had to the accompanying drawings, making part of this specification, in which—

10 Figure 1 is a perspective view of my fastener applied to a door-casing and door. Fig. 2 is a horizontal section through the center of the same. Fig. 3 is a front elevation illustrating the fastener in the position which it occupies when not in use. Fig. 4 is a section on the line *xx* of Fig. 3.

My invention has for its object to provide a simple device by means of which a door can be securely fastened, and at the same time tightened, if loose, to exclude wind and rain, the said device being made adjustable to vary the pressure upon the door, according as the latter may fit more or less closely within its frame or casing; and to this end my invention consists 25 in a cam-lever pivoted to an arm swiveling and made adjustable upon a post or support secured to the door-frame, the arm and its cam-lever being swung on the arm-pivot into a position in front of the door to allow the cam-
30 lever to act upon and fasten the same, the lever and its arm being adapted to drop down out of the way when the door is to be opened, as hereinafter more particularly set forth.

In the said drawings, A represents a door, 35 and B the door frame or casing, to which is secured at any desired height a horizontally-projecting post or support, D, having a base-plate, *b*, through which pass the fastening-screws *c*; but the post D may be secured in 40 place by any other suitable means, if preferred.

The post D is provided with a screw-thread, over which is turned a cap or head, G, having a corresponding screw-thread, and from this swiveling-head G projects laterally an arm, H, 45 to the outer end of which is pivoted at *d* a cam-lever, I, the cam-shaped end *e* of which is adapted, when the lever is moved in the proper direction, to press upon a bearing-plate, L, secured to the door A when the arm H is 50 swung around the post D as a center and brought into a position in front of the door, as

seen in Figs. 1 and 2, thus securely fastening the door and at the same time exerting a strong pressure thereon, so that if it does not properly fit the frame or casing it will be tightened so as to effectually prevent the entrance of cold air or water. When the cam-lever is 55 released by throwing it back, the arm H and the lever will drop down out of the way of the door into the position seen in Fig. 3, when the door is free to be opened.

The head G is preferably made to turn very easily upon its pivotal post D, which insures the arm H dropping automatically out of the way of the door as soon as the cam-lever is 65 thrown back to relieve its pressure.

By turning the swiveling-head G around the screw pivot or post D, the arm H may be adjusted toward or from the casing B to vary the pressure of the cam-lever I to suit the particular door to which the fastener is applied, thus insuring the door being always closed tightly into its frame, and if the door is warped out of shape, or fails to fit properly at some particular portion of its length, I prefer to apply 75 the fastener at or near such point where the greatest pressure is required to produce a close fit.

The bearing-plate L is preferably provided with a groove, *f*, for the reception of the end 80 *e* of the cam-lever I, which is thus securely held in its proper central position when in use, and prevented from slipping down or being thrown off the plate by any sudden jar or other disturbing influence in the event of its not being 85 adjusted to press with much force upon the door.

The above-described device is easily and quickly applied, and forms a secure and reliable door-fastening, which cannot be opened 90 or tampered with from the outside, while the closing of the door tightly into its frame prevents the entrance of cold drafts of air and enables a house to be more easily kept warm in cold weather.

What I claim as my invention, and desire to secure by Letters Patent, is—

1. The combination, with a post or support, D, adapted to be attached to the door frame or casing, of an arm, H, swiveling on said support, and the cam-lever I, pivoted to the arm H and adapted to exert a pressure upon the 95 100

door to fasten and tighten the same, the arm and cam-lever being adapted to swing down out of the way when the lever is released to unfasten the door, substantially as set forth.

5 2. In a door-fastener, the combination of the post D, having a screw-thread, the arm H, having a threaded head, G, adapted to turn or swivel upon said post, whereby its distance from the door-frame may be adjusted, the cam-lever I, pivoted to the arm H, and the bearing-plate L, for receiving the pressure of the cam-lever, all constructed to operate substantially 10 in the manner and for the purpose described.

3. The combination, with the swiveling arm H and cam-lever I, of the bearing-plate L, having a groove, f, for receiving the end of the cam-lever and retaining it in place upon the plate, substantially as set forth.

Witness my hand this 29th day of March,
A. D. 1886.

JAMES E. WHITE.

In presence of—

P. H. TESCHEMACHER,
W. J. CAMBRIDGE.
